UNITED STATES PATENT OFFICE.

LYMAN DAVID BROUGHTON, OF HARTFORD, CONNECTICUT, ASSIGNOR TO UNDERWOOD TYPEWRITER COMPANY, A CORPORATION OF DELAWARE.

TYPE-WRITING MACHINE.

1,102,238.

Specification of Letters Patent.

Patented July 7, 1914.

Application filed November 13, 1911. Serial No. 659,948.

To all whom it may concern:

Be it known that I, LYMAN D. BROUGHTON, a citizen of the United States, residing in Hartford, in the county of Hartford and 5 State of Connecticut, have invented certain new and useful Improvements in Type-Writing Machines, of which the following is a specification.

My invention relates to line-locking devices and marginal stops for typewriter carriages.

I have illustrated my improvement as applied to an Underwood front strike typewriter, illustrated in Patent No. 990,834, 15 dated May 2, 1911.

Beneath the fixed front bar which usually carries the scale plate a bar is attached which may be of T section, and on the front face of this are cut teeth. In front of this 20 bar is a rock bar, which operates a signaling and locking device for the type keys. On this rock bar, are slideable stops which have pivoted members arranged to interlock with the teeth of the rack on the first bar, and 25 thus lock the stop in any position. Around one of the stops is placed a yoke, which carries a tappet to be moved by a cam on the carriage. This yoke is splined on the rock bar, and serves to rotate it, and thus operate 30 the signaling mechanism whenever the cam on the carriage passes this stop carrying the yoke. The stop which does not carry the yoke has a projection with a cam face, and a stop on the opposite side of said cam face. 35 On the carriage is a latch co-operating with this stop and cam so that the carriage can be pulled back only as far as the stop, but if by any means it passes beyond the stop, the co-operating latch on the carriage will 40 ride over the cam face, and so prevent the machine from being locked against operation. To enable the carriage to pass this stop, the co-operating latch on the carriage is pivoted so that it can be readily raised out of 45 the path of the stop. The stops are so arranged that the handle operating the locking member swings to one side, and a finger rest is conveniently placed near the handle so that the stop can be released and 50 moved along with one clasp of the fingers. In one direction the stop can be released and adjusted by a single pressure on the handle in said direction.

One advantage of my improvement is that 55 the stops are easily moved, that they can be

set in any position whatsoever because the rocking bar and rack bar may extend entirely across the machine; the rack bar may be easily attached to almost any machine, and the arrangement of the tappet on the 60 rock bar enables the operation of the locking mechanism to be much more sure than is ordinarily the case.

Other objects and advantages will hereinafter appear.

In the accompanying drawings, Figure 1 is a perspective view looking upward from the front of the machine, showing the stops, rack bar, and adjacent parts. Fig. 2 is a fragmentary view of the left-hand end of the 70 machine, showing how one stop operates the locking mechanism. Fig. 3 is a view of the stops as seen from above. Fig. 4 shows the stops as viewed, from behind when in position on the machine.

In the drawings, pillars 1 at opposite sides of the machine form part of the machine frame. On these pillars is mounted a fixed cross bar 2 spaced above the pillars by means of blocks 3. In the rear face of the cross 80 bar 2, and extending longitudinally thereof, is a channel 4, in which runs a carriage-supporting roller 5. On the front bar 6 of the carriage is mounted a cam 7 and a right-hand marginal stop 8.

On the under face of the bar 2 is held by screws 9, a T-shaped bar 10, which has a tongue 11 seated in a groove in said bar 2, and on the front face of said T-shaped bar is cut a rack 12. Also supported by said 90 front bar 2 by means of brackets 13, is a rock bar 14, which carries the marginal stops 15 and 16. These stops are locked by engagement with the rack 12 and serve to limit the movement of the carriage in each direction.

Extending on opposite sides of the stop 15 is a member which may be in the form of a yoke 17 splined on the rock bar 14 and carrying a tappet 18 which co-operates with the cam 7 on the carriage to ring a bell and to operate the mechanism for locking the type keys. The cam on the carriage comprises a part 19 arranged to slightly depress the tappet 18 and rock the bar 14 so as to 105 swing forward an arm 20 attached to the rock bar. On the lower end of said arm 20 is pivoted a swinging trip 21 which normally rests in a notch 22 in a lever 24 which carries the clapper 25 of a bell 26. When 110

arm 20 is swung forward by the tappet 18 as described, the trip 21 rides over a projection 23, camming the forward end of the lever 24 downward. This movement momentarily raises the clapper and causes the bell to be rung. The carriage, in its further movement, brings a projection 27 of the cam 7 over the tappet 18, and this causes a further movement of the arm 20 which is thereby swung into the position shown in Fig. 2, where it has moved rock arm 27 on shaft 28 to bring locking bar 29 under hooks 30 of the keys 31, and thus prevent their being depressed. If it is desired to write a few more characters, a button 32 may be pressed, thus camming the arm 20 to one side, and carrying the pin 36 clear of rock arm 27. This releases the locking member 29 and again permits the keys to be depressed. On further movement of the carriage, a portion 34 of the cam comes over the tappet and again locks the keys, and a ledge 35 on the stop 7 strikes against a projection 36 on stop 15 to prevent any further movement of carriage whatsoever, thus holding the machine completely locked with the carriage at the limit of its movement to the left. On the stop 16 is a projection 37 which is adapted to strike against a latch 38 on the front bar 6 of the carriage in its movement toward the right, and thus limit the right-hand margin. This latch may be raised by a handle 39 to clear said projection, and thus extend the writing to any desired point. A cam surface 40 is provided on the side of said projection 37, so that in its letter-feeding movement, the carriage will cause the latch 38 to ride down beneath said projection 37, and permit the latch to pass the stop. The stops 15 and 16, as has been stated, are slideable along bar 14. They embrace said bar, but rotate easily around it, and each has pivoted thereon by means of a screw 41, a horizontally swinging arm 42, which carries teeth 43 forming a dog adapted to lock in the teeth 12 of the T-shaped bar 11. The arm 42 may extend laterally and rearwardly from its pivot, as shown at 44, in order to provide a good bearing for the pin 41, and it may work in the horizontal plane of the rack bar and in front thereof, the whole device making a compact structure. On each swinging arm 42 is a handle 45, whereby the arm may be swung clear of the rack 12. On the body of each stop 15, 16, is mounted a plate 46 carrying a finger rest 47, enabling the fingers to readily clasp the handles 45, and move the stops along to any desired position. The swinging arms 42 are automatically sprung into engagement with the teeth 12 by means of springs 48. The stops 15 and 16 extend rearwardly beneath the T-shaped bar 10, and thence upwardly and forwardly to embrace the rear flange 49 of said bar. The front of each

stop is likewise extended upwardly and rearwardly to form a shelf 51 covering the teeth 12 of said bar. Thus each stop forms a channel 50 to receive the bar 10. Collars 52 are fast on the rock bar 14, in order to hold it from sliding, and a flat surface 53 of said bar permits the yoke 17 to slide along it and yet positively throw it. On the return of the carriage, the locking mechanism is released, and the bell ringing mechanism reset by means of a spring 54 which swings the arm 20 into its normal position, while the swinging trip 21 rides over the projection 23.

It will be seen, therefore, that my invention furnishes a simple construction in which the stops can be quickly adjusted and the parts readily replaced if injured, or added to machines of existing construction.

Variations may be resorted to within the scope of the invention, and portions of the improvements may be used without others.

Having thus described my invention, I claim:

1. In a typewriter, the combination of a carriage, a rock bar, a second bar having teeth on one vertical face, right and left hand margin stops each embracing both of said bars, said rock bar being rotatable in said stops, a swinging member on each stop, and a tooth on each swinging member to engage with said toothed bar to hold the stop.

2. In a typewriter, the combination with a rock bar, of a rack bar having teeth cut on its vertical face, stops each embracing both of said bars, members pivoted to said stops and swinging in a horizontal plane, teeth on said members to engage said rack to hold the stops adjusted, handles for swinging said pivoted members, springs holding said teeth engaged, and a yoke splined on the rock bar embracing one of said stops to be moved by the carriage to swing said bar.

3. In a typewriting machine, the combination, with a traveling carriage, of a rock bar adjacent said carriage, a stop slideable on and rotatable around said bar, a yoke embracing said stop and splined on said bar, a track on the frame on which said carriage runs, a toothed bar underlying said track and having a bearing substantially throughout its length on the under surface of said track, teeth on the face of said toothed bar adjacent said stop, and a tooth pivoted on said stop to swing in the plane in which it is slideable and arranged to lock said stop by said rack.

4. In a typewriter, the combination of a carriage, a rock bar moved by the carriage, a T-shaped bar having teeth in the vertical face of one member thereof, right and left hand margin stops, each embracing both bars and adjustable along substantially the whole length of said rock bar, teeth in said stops to engage in said T-shaped bar to hold

said stops adjusted, a yoke embracing one of said stops and splined on the rock shaft, and a tappet on said yoke moved by the carriage.

5. In a typewriter, the combination with a carriage, of a fixed bar across the front of the machine upon which the carriage runs, a rack bar having teeth in its vertical front face and supported beneath said fixed bar, a rock bar, right and left hand margin stops each slidably supported on both said rock bar and said rack bar, members pivoted to said stops and revolving in a horizontal plane, and teeth on said pivoted members to engage with said rack.

6. In a typewriter, the combination with a carriage, of a fixed bar across the front of the machine upon which the carriage runs, a T-shaped bar located under and supported from said fixed bar, teeth cut on the front of said T-shaped bar, a rock bar, right and left hand margin stops each embracing said rock bar and said T-shaped bar, pivoted members on said stops turning in a horizontal plane, and teeth on said pivoted members to hold the stops adjusted.

7. In a typewriting machine, the combination of a machine frame having a rabbet thereon, and a rack bar with rack teeth on its front face and formed with a rib seated in said rabbet.

8. In a typewriting machine, the combination with a machine frame and a carriage supporting and guiding rail extending there across, of a T-shaped rack bar beneath said rail, said rack bar having an upwardly extending rib bearing against the under face of said rail substantially through out the length of the rack bar, a margin stop mounted on the rack bar, and means to lock said stop in adjusted position along the bar.

9. In a typewriting machine, the combination with a machine frame and a carriage supporting and guiding rail extending thereacross, of a T-shaped rack bar beneath said rail, said rack bar having an upwardly extending rib bearing against the under face of said rail substantially throughout the length of the rack bar, said rack bar being formed with teeth on its front face, a rod parallel with the rack bar, margin stops on said rod and slideable therewith, and locking dogs pivoted to said stops for movement in a plane parallel with said rod and movable into and out of locking engagement with said rack teeth.

10. In a typewriter, a front bar on which the carriage is arranged to travel, an inverted T-shaped bar attached to the under side of said front bar and having teeth forming a rack on its vertical front face, a rock bar carrying stops, each stop having a dog mounted therein by a vertical pivot, said dog swinging to and from said rack in the horizontal plane thereof, and a forwardly

extending operating handle on said dog to be swung in the direction of travel of said stop, to permit the release and advance thereof by the application of a single manual impulse to said handle.

11. In a typewriting machine, the combination with a traveling carriage, of a rock bar adjacent said carriage, a stop slideable on and rotatable around said bar, a yoke embracing said stop and splined on said bar, a rack bar on the frame of the machine having teeth facing forwardly toward said rock bar, said stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.

12. In a typewriting machine, the combination with a traveling carriage, of a rock bar adjacent said carriage, a pair of stops each slideable on and rotatable around said bar, a yoke embracing one stop and splined on said bar, a rack bar on the frame of the machine having teeth facing forwardly toward said rock bar, each stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.

13. In a typewriting machine having a front bar on which the carriage is arranged to travel, an inverted T-shaped bar depending from said front bar and having vertical teeth forming a rack on its forward face, a stop slideably engaging said T-shaped bar, a supporting bar for said stop in advance of said rack, said stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.

14. In a typewriting machine having a front bar on which the carriage is arranged to travel, an inverted T-shaped bar attached to and depending from said front bar and having vertical teeth forming a rack on its forward face, a stop slideably engaging said T-shaped bar, a rock bar supporting said stop in advance of said rack, said stop having a dog mounted therein by a vertical pivot, said dog swinging to and from said rack in the horizontal plane thereof, and a forwardly extending operating handle on said dog to be swung in the direction of travel of said stop.

stop, to permit the release and advance thereof by the application of a single manual impulse to said handle.

15. In a typewriting machine having a front bar on which the carriage is arranged to travel, an inverted T-shaped bar depending from said front bar and having vertical teeth forming a rack on its forward face, a stop slidably engaging said T-shaped bar, a rock bar loosely supporting said stop in advance of said rack, said stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.

20. 16. In a typewriting machine having a front bar on which the carriage is arranged to travel, an inverted T-shaped bar depending from said front bar and having vertical teeth forming a rack on its forward face, a stop slidably engaging said T-shaped bar, a rock bar supporting said stop in advance of said rack, said stop having a dog mounted therein by a vertical pivot, said dog swinging to and from said rack in the horizontal plane thereof, a forwardly extending operating handle on said dog to be swung in the direction of travel of said stop, to permit the release and advance thereof by the application of a single manual impulse to said handle, and a tappet-carrying member mounted on said rock bar to rock therewith.

17. In a typewriting machine having a front bar on which the carriage is arranged to travel, an inverted T-shaped bar attached to and depending from said front bar and having vertical teeth forming a rack on its forward face, a stop slidably engaging said T-shaped bar, a rock bar supporting said stop in advance of said rack, said stop having a dog mounted therein by a vertical pivot, said dog swinging to and from said rack in the horizontal plane thereof, a forwardly extending operating handle on said dog to be swung in the direction of travel of said stop, to permit the release and advance thereof by the application of a single manual impulse to said handle, and a tappet-carrying member splined to said rock bar to rock therewith.

18. In a typewriting machine having a

front bar on which the carriage is arranged to travel, an inverted T-shaped bar depending from said front bar and having vertical teeth forming a rack on its forward face, a stop slidably engaging said T-shaped bar, a rock bar supporting said stop in advance of said rack, said stop having a dog mounted therein by a vertical pivot, said dog swinging to and from said rack in the horizontal plane thereof, a forwardly extending operating handle on said dog to be swung in the direction of travel of said stop, to permit the release and advance thereof by the application of a single manual impulse to said handle, and a tappet-carrying member localized with said stop on said rock bar, and adapted to rock with said bar.

19. In a typewriting machine, the combination with a traveling carriage, of a rock bar adjacent said carriage, a stop slideable on and rotatable around said bar, a member splined on said bar and movable thereon with said stop, an inverted T-shaped rack bar attached to the frame of the machine having teeth facing forwardly toward said rock bar, said stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.

20. In a typewriting machine, the combination with a traveling carriage, of a rock bar adjacent said carriage, a pair of stops each slideable on and rotatable around said bar, a member splined on said bar and movable thereon with one of said stops, an inverted T-shaped rack bar on the frame of the machine having teeth facing forwardly toward said rock bar, each stop having a dog mounted therein by a vertical pivot, said dog swinging to and from said rack in the horizontal plane thereof, and a forwardly extending operating handle on said dog to be swung in the direction of travel of said stop, to permit the release and advance thereof by the application of a single manual impulse to said handle.
